UNITED STATES PATENT OFFICE

ISAAC H. BURNSTINE, OF CHICAGO, ILLINOIS

DESIGN FOR A POOL TABLE

Application filed May 1, 1931. Serial No. 39,680. Term of patent 14 years.

To all whom it may concern:

Be it known that I, ISAAC H. BURNSTINE, a citizen of the United States, residing at Chicago, in the county of Cook and State of Illinois, have invented a new, original, and ornamental Design for Pool Table, of which the following is a specification, reference being had to the accompanying drawing, forming a part thereof.

I claim:

The ornamental design for a pool table as shown.

ISAAC H. BURNSTINE.
